CUTLERY HOLDER

Kenneth M. Junker, Ellicottville, N. Y.

Application November 9, 1953, Serial No. 27,512

Term of patent 14 years

(Cl. D44—29)

To all whom it may concern:

Be it known that I, Kenneth M. Junker, a citizen of the United States, residing at Ellicottville, in the county of Cattaraugus and State of New York, have invented a new, original, and ornamental Design for a Cutlery holder, of which the following is a specification, reference being had to the accompanying drawing, forming a part thereof.

holder embodying my new design; Figure 2 is a side elevational view thereof; and Figure 3 is a top plan view of the same.

The cutlery shown in broken lines is for purposes of illustration.

I claim:

The ornamental design for a cutlery holder, substantially as shown and described.
